(57) **CLAIM**

The ornamental design for a television receiver, as shown and described.

DESCRIPTION

1. Television receiver

1.1 : Perspective view in vertical position

1.2 : Front view in vertical position

1.3 : Back view in vertical position

1.4 : Left view in vertical position

1.5 : Top view in vertical position

1.6 : Bottom view in vertical position

1.7 : Back perspective view in vertical position

1.8 : Front view in a partially rotated position

1.9 : Perspective view in horizontal position

1.10 : Front view in horizontal position

1.11 : Back view in horizontal position

1.12 : Left view in horizontal position

1.13 : Top view in horizontal position

1.14 : Bottom view in horizontal position

1.15 : Back perspective view in horizontal position

Reproduction 1.1 is a front perspective view of the television receiver; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is a back perspective view thereof; reproduction 1.8 is a reference view showing the intermediate state that the display is rotating and forms no part of the claimed design; reproduction 1.9 is a front perspective view thereof in a condition that the display has been rotated at 90 degrees; reproductions 1.10 to 1.15 are the front, back, left, top, bottom and back perspective views of reproduction 1.9.

1 Claim, 15 Drawing Sheets
